J. E. OSMER.

FLUID PRESSURE MOTOR.

APPLICATION FILED OCT. 8, 1906.

937,384.

Patented Oct. 19, 1909.

Minneapolis, Oct. 19, 1909.

Mr. Harry L. Chindall

Inventor:

J. E. Osmor

By Luther L. Miller, Atty.

UNITED STATES PATENT OFFICE.

JOHN E. OSMER, OF CHICAGO, ILLINOIS, ASSIGNOR TO ELEVATOR SUPPLY & REPAIR COMPANY, OF CHICAGO, ILLINOIS, A CORPORATION.

FLUID-PRESSURE MOTOR.

937,384.

Specification of Letters Patent. Patented Oct. 19, 1909.

Application filed October 8, 1908. Serial No. 337,842.

To all whom it may concern:

Be it known that I, JOHN E. OSMER, a citizen of the United States, residing at Chicago, in the county of Cook and State of Illinois, have invented certain new and useful Improvements in Fluid-Pressure Motors, of which the following is a specification.

This invention relates to a motor of the same general form as the motor shown and described in Patent No. 899,999, issued to me September 29, 1908, said motor being designed particularly for opening and closing doors, for operating railway switches, and for similar purposes. The motor comprises a high-pressure cylinder and a low-pressure cylinder arranged in tandem, the pistons of said cylinders being arranged to move together and being operatively connected with the door or other device to be moved.

One of the objects of this invention is to produce a valve mechanism especially adapted for controlling motors of the class referred to.

Another object is to provide means for admitting an extra amount of pressure fluid to the low-pressure cylinder for building up the working pressure therein.

In the accompanying drawings, Figure 1 is a longitudinal central section through a fluid-pressure motor embodying the features of my invention. Figs. 2, 3, and 4 are detail sectional views showing the different positions of the valve mechanism. Fig. 5 is a detail sectional view showing the valve face. Fig. 6 is a view illustrating an alternative construction of the valve mechanism, the same being represented in the position corresponding to that shown in Fig. 2.

The embodiment herein shown of my invention comprises a high-pressure cylinder 1 and a low-pressure cylinder 2 arranged in tandem, and formed, in this instance, of an integral casting. The motor is adapted to be secured to any suitable support by means of lugs 3 cast integral with the cylinders 2 and 3. The pistons 4 and 5 for the cylinders 1 and 2, respectively, are fixed to the opposite ends of a rack bar 6. Between its ends the rack bar 6 is supported upon a bearing shoe 7 adjustably mounted in the cylinder structure. Bearing lugs 8, preferably cast integral with the cylinder frame, rotatably support a shaft 9. Said shaft has fixed thereto a sector 10 adapted to mesh

with the rack bar 6, the cylinder structure 55 having a slot 11 formed therein to receive said sector. Upon one end of the shaft 9 is fixed a lever 12 operatively connected with the door or other device to be moved.

The valve mechanism that controls the 60 passage of pressure fluid to and from both cylinders is located upon the outer end of the high-pressure cylinder 1. Upon said cylinder 1 is a pressure chest 13 adapted to be placed in communication with suitable 65 supply of pressure fluid by means of an inlet pipe 14, said pipe being screwed into either one of two threaded openings 15 formed in the walls of said pressure chest, the opening not used being closed by a plug 16. 70 A port 17 is connected at one end with the interior of the low-pressure cylinder 2 by means of the pipe 18. An inlet port 19 and an exhaust port 20 communicate with the port 17 and open upon the valve face 21. 75 The pressure chest 13 is connected with the high-pressure cylinder 1 by a port 22. An exhaust port 23 communicates between the valve face 21 and the atmosphere. A slide valve 24 is slidably mounted between guides 80 25 formed upon the valve face 21, said slide valve having upon its face a groove 26 adapted to connect the ports 19 and 22, and a groove 27 adapted to connect the ports 20 and 23. In the slide valve 24 is also formed 85 an opening 28 extending through said slide valve and located in position to be brought into register with the exhaust port 20. The slide valve 24 is reciprocated by means comprising a crank disk 29, said crank disk 90 being mounted upon the lower end of a vertical shaft 30 rotatably mounted in a bearing 31 upon the upper wall of the pressure chest 13. Fixed to the under side of the crank disk 29 is a crank pin 32 adapted to lie within a transverse groove 33 in the slide valve 24. The shaft 30 is rocked to reciprocate the slide valve 24 by means of a crank arm 34 connected in any suitable way to a controller (not shown) located 95 100 within convenient reach of the operator.

Assuming the parts to be in the position shown in Fig. 1, the operation of the motor is as follows: The high-pressure cylinder 1 is connected with the pressure chest 13 through the port 22, and the low-pressure cylinder 2 is connected with the atmosphere through the pipe 18, the port 17, the exhaust

port 20, the groove 27, and the exhaust port 28. The pistons 4 and 5 are consequently moved toward the left (Fig. 1) by the pressure of the fluid within the high-pressure cylinder 1. When it is desired to reverse the movement of the door or other device being operated, the operator moves the slide valve 24 into the position shown in Fig. 4, wherein the cylinders 1 and 2 are placed in communication with each other through the passages 22, 26, 19, 17, and 18, equalizing the pressures in said cylinders. The piston 5 in the low-pressure cylinder having a larger area than the piston 4 in the high-pressure cylinder, the total pressure exerted upon the piston 5 will be greater than the total pressure exerted upon the piston 4, causing a movement of said pistons toward the right. If now it be desirable to increase the pressure in said cylinders, the slide valve 24 is moved to the position shown in Fig. 3, causing the opening 28 to register with the port 20, and thereby permitting the entrance of high-pressure fluid to the cylinders 1 and 2. The movements of the valve 24 being under the control of the operator, said valve may be moved to admit an extra amount of pressure fluid whenever and in the amounts necessary. When the pressure has been augmented to the desired degree, as indicated by the movement of the door, the operator moves the valve 24 from the position shown in Fig. 3 to that shown in Fig. 4. Such movement is sufficient to carry the opening 28 out of register with the port 20, thereby cutting off the supply of high-pressure fluid to the cylinders, but it is not sufficiently great to carry the groove 26 out of register with the ports 19 and 22, thus leaving the cylinders 1 and 2 in communication with each other. As will be understood, the slide valve 24 may be moved back and forth slightly to bring the opening 28 into register with the port 20 at intervals to build up the pressure in the cylinders as needed.

In Fig. 6 I have illustrated a modified construction wherein the end of the slide valve 24 is partially cut away, as at 35, so as to permit of covering and uncovering the port 20 in the same manner as the opening 28 is made to coincide with said port.

As the movements of the valve member 24 are under the direct control of the operator, he is enabled to manipulate the mechanism as required. To illustrate, it is desirable, as hereinbefore stated, to cushion or retard the movements of the door near the ends of its travel. This may be accomplished by slightly shifting the valve member 24 from the positions shown in Figs. 2 and 4, thus cutting off communication to a greater or less extent between the low-pressure cylinder and the exhaust or between the high-pressure cylinder and the low-pressure cylinder.

The escape of the air contained in the space in front of the advancing piston being thus retarded, the movement of the door near the ends of its travel are cushioned or retarded, thereby preventing slamming of the door, and possible injury to persons standing in the doorway. The same result may be obtained by making the inlet port 22 and the exhaust port 23 quite small or restricted. When high-pressure fluid is admitted to the high-pressure cylinder 1, the exhaust from the low-pressure cylinder 2 will be somewhat choked, thus providing a cushion near the end of the travel of the pistons toward the left, Fig. 1. Constricting the passage 22 results in a similar effect when the pistons 1 and 2 are placed in communication with each other and the pistons are traveling toward the right, Fig. 1.

I claim as my invention:

1. In a fluid pressure motor, in combination, an intermittently-operating cylinder; two sources of pressure fluid at varying pressures; and a distributing valve mechanism for said cylinder controlled by the operator and movable through variable distances by the operator, and adapted to connect said cylinder with either of said sources of pressure fluid.

2. In a fluid pressure motor, in combination, a high-pressure cylinder and a low-pressure cylinder said cylinders operating intermittently; a pressure chest; a valve mechanism comprising a slide valve in said pressure chest, the movements of said valve being controlled by the operator, and said slide valve being reciprocable through variable distances by the operator, said mechanism comprising means for connecting said high-pressure cylinder with said pressure chest, and for connecting said cylinders together, said mechanism also comprising means for connecting said low-pressure cylinder with said pressure chest.

3. In a fluid pressure motor, in combination, a high-pressure cylinder and a low-pressure cylinder; a pressure chest; and a valve mechanism comprising a slide valve in said pressure chest; a valve face, said valve face being connected with said cylinders by means of ports, said slide valve having a groove adapted to connect said ports, said slide valve also being adapted to permit the passage of fluid from said pressure chest to said ports while said ports are connected together by said groove.

4. In a fluid pressure motor, in combination, a high-pressure cylinder and a low-pressure cylinder said cylinders operating intermittently; and a single valve member movable variable distances by the operator for placing said high-pressure cylinder in communication with a source of pressure fluid, for connecting said cylinders together, and for connecting said low-pressure cylinder

der with the exhaust, said member also being adapted to connect said low-pressure cylinder with the source of pressure fluid.

5. The combination, with two cylinders, one of said cylinders having a valve face thereon, one of said cylinders communicating with said valve face by means of an inlet port, the other cylinder communicating with said valve face by means of two inlet ports, 10 said valve face having an exhaust port there-

in; and a slide valve having a groove therein adapted to connect said first mentioned inlet port with one of the last mentioned ports, said valve also having a groove adapted to connect the other of said last mentioned inlet ports with said exhaust port. 15

JOHN E. OSMER.
